(57) **CLAIM**

The ornamental design for a reflective cap, as shown and described herein.

DESCRIPTION

FIG. 1 is a front perspective view of a first embodiment of a reflective cap showing my new design;

FIG. 2 is a right side elevational view of FIG. 1, the left side view being a mirror image thereof;

FIG. 3 is a magnified view of a first reflective portion shown in FIG. 2;

FIG. 4 is a magnified view of a second reflection portion shown in FIG. 2;

FIG. 5 is a top view of FIG. 1;

FIG. 6 is a magnified view of a third reflective portion shown in FIG. 5;

FIG. 7 is a bottom view of FIG. 1;

FIG. 8 is a front view of FIG. 1;

FIG. 9 is a back view of FIG. 1;

FIG. 10 is the front perspective view of a second embodiment of a reflective cap;

FIG. 11 is a right side elevational view of FIG. 10, the left side elevational view being a mirror image thereof;

FIG. 12 is a magnified view of a first reflective portion shown in FIG. 11;

FIG. 13 is a top view of FIG. 10;

FIG. 14 is a magnified view of a second reflective portion shown in FIG. 13;

FIG. 15 is a bottom view of FIG. 10;

FIG. 16 is a front view of FIG. 10; and,

FIG. 17 is a back view of FIG. 10.
